Robert I. Erlichman,

BY

J. Stuart Freeman,
ATTORNEY.

UNITED STATES PATENT OFFICE.

ROBERT I. ERLICHMAN, OF PHILADELPHIA, PENNSYLVANIA.

PISTON PACKING-RING.

1,354,287.

Specification of Letters Patent. Patented Sept. 28, 1920.

Application filed May 14, 1919. Serial No. 297,171.

To all whom it may concern:

Be it known that I, ROBERT I. ERLICHMAN, a citizen of the United States, residing in Philadelphia, in the county of Philadelphia, State of Pennsylvania, have invented a new and useful Piston Packing-Ring; and I do hereby declare the following to be a full, clear, and exact description of the invention, such as will enable others skilled in the art to which it appertains to make and use the same.

The object of this invention is to provide an improved piston packing ring, which is applicable to pistons of any type, but particularly those forming a part of an internal combustion engine.

Another object is to form such a packing ring in such manner as to prevent leakage of steam or gases of combustion past the piston carrying such ring; and simultaneously to aid in lubricating the cylinder walls throughout their complete circumference.

And a further object of the invention is to provide a piston-ring having a transversely extending zig-zag severance at one portion to permit expansibility and contractibility of said ring, while the outer circumferential surface of the ring is provided with a groove which may be said to wander from one to the other edge portions of the ring surface. This groove in shape partakes of the nature of that type of grooves which form a characteristic detail of cylinder- or drum-cams. Consequently, for the purpose of this description and the claims appended hereto, the term cam or wandering groove is used in order to denote the shape of groove just referred to.

With these and other objects in view, the improved device comprises details of construction and operation fully brought out in the following description, when read in conjunction with the accompanying drawings, in which Figure 1 is a development of the outer circumferential surface of the improved piston packing ring; Fig. 2 is a side elevation of the ring in normal shape; and Fig. 3 is a transverse section of a portion of the ring taken on the line 3—3 of Fig. 1.

Referring to the drawings, a ring is provided having exterior and interior circumferential surfaces 1 and 2, respectively, and made of a suitable type as to afford the required resiliency which is characteristic of an article of this nature.

For the purpose of describing the details of the device, it should be said that the ring is bounded transversely by plane faces 3 and 4, while circumferentially the ring is milled out from opposite sides to provide recesses 5 and 6, said recesses being bounded by aligned central walls 7 and 8 and at their ends by angularly extending walls 9 and 10, while the end portion having the recess 5 terminates in an angularly disposed wall 11 parallel with the wall 10, and the other end portion of the ring terminates in a similar angularly disposed wall 12 parallel with the wall 9. This construction obviously makes it possible for the adjacent end portions of the ring to constantly coöperate in sliding engagement along the walls 7 and 8 substantially regardless of the extent to which the ring expands and contracts, both in accordance with the heat and the diameter of the cylinder employed.

The exterior surface 1 is then provided with a groove defined by an obliquely extending wall 13 and a much more perpendicularly extending wall 14, it being particularly noticeable that said groove wanders as it were from the side 3 to the side 4 and back again to the side 3, as the groove is traced from the recess 5 around the circumference of the ring to the recess 6.

This formation of the groove 13—14 is provided in order that, as the piston carrying the ring causes the latter to travel in the direction of the arrow A, the wall 14 of said grooves tends to scrape a portion of the oil film from the surface of the piston cylinder, the oil lodging within said groove. However, it will be readily noticeable that oil can more readily enter the groove in question where it terminates in the recess 5 as the ring travels in the direction stated, wherefore, the diametrically opposite portion of the groove is purposely brought as near as convenient to the side wall 4, in order that the traveling of the ring will force this oil adjacent to the ends of said grooves circumferentially in opposite directions, until after successive piston strokes at least a portion of it has progressed to that portion of the groove shown in the center of Fig. 1. With this construction, the tendency of this particular type of groove is to insure a uniform lubrication between the ring and the surrounding cylinder throughout the entire circumferential extent of the two.

Wherefore, it has been found that a piston packing ring constructed in accordance with the foregoing description naturally increases the efficiency and decreases the wear 5 of the slidably co-operating surfaces within a cylinder of a given engine, and that the combination of said groove with the lap-joint hereinbefore described offers the simplest construction which it has been possible 10 to devise to accomplish the purpose desired.

Having thus described my invention, what I claim and desire to protect by Letters Patent of the United States is:—

1. A packing ring, provided upon its exterior surface with a circumferentially extending cam-groove, the surfaces defining said groove being oblique with respect to the adjacent surface of the ring and converging inwardly.
2. A packing ring, having a transversely extending cut to permit expansibility and compressibility of the ring, and a wandering-groove in the exterior surface of the ring, said groove extending from one side of said 25 cut circumferentially of the ring to the other side of said cut, and alternately from one side of the ring transversely of its outer surface to the other side of the ring.
3. A packing ring, having a transversely extending cut to permit expansibility and compressibility of the ring, and a wandering-groove in the exterior surface of the ring bounded by inwardly converging surfaces, and one of the surfaces of said groove 35 being at an obtuse angle to the adjacent exterior surface of the ring.
4. A packing ring, having a zig-zag severance at one point to provide flexibility of the ring, and a circumferentially extending wandering-groove in the exterior surface of the ring, having one of its defining surfaces lying at an obtuse angle with the said exterior surface, to provide an under-cut 40 pocket and an overhanging ledge.
5. A packing ring, having a zig-zag severance at one point to provide flexibility of the ring, and a circumferentially extending wandering-groove in the exterior surface of the ring, having its defining surfaces converging inwardly and the bisector of the 45

angle formed by said last-named surfaces extending in a diagonal direction from the entrance to the groove.

6. A packing ring, provided upon its exterior surface with a circumferentially extending cam-groove, the surfaces defining said groove being oblique with respect to the adjacent surface of the ring and converging inwardly, one of the surfaces defining said groove lying at an obtuse angle 55 with the adjacent surface of the ring, to form an under-cut circumferentially elongated pocket, and an overhanging edge portion.

7. A piston packing ring, comprising a member having a cylindrical outer surface and transversely severed to permit expansibility and compressibility of the ring, and the said surface being provided with a circumferential groove wandering alternately 65 from one to the other of the laterally opposite sides of said member and defined by two laterally opposite surfaces converging inwardly at an acute angle, and the bisector of said angle extending at an acute angle 70 with the said outer surface.

8. A piston packing ring, comprising a member having a cylindrical outer surface and transversely severed to permit expansibility and compressibility of the ring, and the said surface being provided with a circumferential groove wandering alternately 80 from one to the other of the laterally opposite sides of said member and defined by two laterally opposite surfaces converging inwardly at an acute angle, and one of said 85 surfaces forming with the adjacent portion of the said outer surface an acute angle, to provide an under-cut recess bounded by an overhanging edge portion adapted to scrape the surfaces of a surrounding piston cylinder.

In testimony whereof I have signed my name to this specification, in the presence of two subscribing witnesses.

ROBERT I. ERLICHMAN.
